(57) **CLAIM**

We claim the ornamental design for an information handling system carrying case, as shown and described.

DESCRIPTION

FIG. 1 is a front perspective upper view of the information handling system carrying case in a closed position comprising the present invention;

FIG. 2 is a front side view thereof in a closed position;

FIG. 3 is a rear side view thereof in a closed position;

FIG. 4 is a right side view thereof in a closed position;

FIG. 5 is a left side view thereof in a closed position;

FIG. 6 is a top view thereof in a closed position;

FIG. 7 is a bottom view thereof in a closed position;

FIG. 8 is a bottom perspective view thereof in a closed position;

FIG. 9 is a rear perspective view thereof in an open position having a keyboard portion coupled to the carrying case with a tablet information handling system supported in a viewing position; and,

FIG. 10 is a right side view thereof in an open position having a keyboard portion coupled to the carrying case with a tablet information handling system supported in a viewing position.

Broken lines shown in the drawings illustrate portions of the information handling system carrying case, and form no part of the claimed design.

1 Claim, 8 Drawing Sheets
